MULTIPHASE EQUIPMENT PROTECTION.

Application filed March 17, 1922, Serial No. 544,485. Renewed June 2, 1928.

This invention relates to improvements in electrical fuses and a method of connecting the same in power lines to protect equipment operated by multiphase current, and refers 5 more particularly to fuses which may be so connected in power lines that if the fuse in one line is blown the fuses in the remaining phase lines are also blown, thereby disconnecting the power source from the system.

10 Among the salient objects of the invention are to provide fuses which are particularly adapted to be connected up in power lines serving as connections between generators and motors, the fuses being so connected that 15 the motor or other equipment cannot be operated on any but the required number of phases.

Fig. 1 is a diagrammatic showing of a three phase motor and generator hook-up with the 20 fuses inserted in the separate phase line.

Fig. 2 is a cylinder system showing a modified form of fuse being used in the lines.

Referring to the details of the drawings, at 1 is shown a motor generator which supplies 25 current to operate the motor 2. The current is supplied through three separate phases or lines designated as 3, 4 and 5. At 6 is interposed a knife switch which may be thrown out when the power is to be cut off. To follow the course 30 of the initial phase, follow the line 3 through the knife switch and into the bottom of the cylindrical fuse 7. The three fuses, 7, 8 and 9 are identical in structure, having a lower metallic cap 10, a fiber cylindrical body portion 11 and a top metallic cap 12. Two side connections or binding posts are positioned in the body portion at 13 and 14. A lower contacting spring 15 is soldered or otherwise fastened to the lower metallic cap and makes a 40 connection therethrough with the wire 3 and an upper contacting spring 16 attached to the upper cap and likewise makes a contact therewith. The two springs are fastened to the binding post 14 by means of a fusible substance such as lead shown at 17. Similar 45 metal is interposed between the two springs as shown at 18. The particular type of construction of the fuses may vary in numerous details without departing from the scope of the invention, as the particular method of connecting the springs with the caps and the binding post connections in the side of the body of the fuse offer innumerable opportunities for variation. The current supplied through the line 50 3 proceeds through the spring 15 and thence on through the spring 16 and out through the upper wire connection 3 to the motor 2. A second phase supplied from the generator flows through the intermediate wire 4 and through the middle fuse 8 in an identical 60 manner as that explained in 7 and out through the upper connecting line 4 to the motor 2. The third phase supplied from the generator through the wire 5 proceeds through the knife switch 6 and fuse 9 to the motor 2 65 through the upper connecting line 5.

If for some reason or other the load upon the separate lines becomes unbalanced or an excess load is thrown upon the line 5, the fuse 9 will be blown as is shown in Fig. 1. Under 70 such a condition the fusible metal which serves to hold the contacting springs to the side binding post 14, will be fused and the springs released. With the release of the lower spring it will snap over and contact 75 with the binding post 13 on the opposite side of the body portion of the fuse 9. This makes a connection through the resistance wire 19 and causes the fusing of the lead which holds the contacting springs in the fuse 8. With the 80 releasing of the lower spring 15 in the fuse 8 this will snap over into a position shown by the spring in the fuse 9 and contact with the projecting portion of the binding post 13 in the body portion of the fuse 8 which in turn 85 will short circuit the fuse 7 in the same manner, thereby cutting off the entire current of the generator from the motor.

It is obvious, of course, that the blowing 90 of the fuses is practically simultaneous so that immediately with the blowing of one fuse the entire current is cut off from the motor.

At the present time with the common type 95 of fuse it is often possible and a common happening for one fuse to blow out and the motor hum along on two phases. It is not long under operation of this sort before the motor is completely burnt out and must be rewound before it can be again satisfactorily used.

Where a motor is not constantly attended and 100 carefully watched, it is extremely desirable to have some means of cutting the current or notifying an operator in case one of the lines becomes shorted or disconnected, as it takes a very short period of time to ruin a motor 105 when operating on anything less than the proper number of phases. It is understood that the operator is not restricted to a three phase operation as any system which employs fuses for protecting the separate lines, may be 110 hooked up in this manner.

In Fig. 2 a similar type of construction is

shown, the power being supplied from the generator 20 and the current passing through the separate lines 21, 22 and 23 in which are interposed the fuses 24, 25 and 26. The construction of the fuses is somewhat different from those shown in Fig. 1 as there is positioned in the body of the fuse a plunger 27 which is attached to the lower cap by means of a tension spring 28. The plunger is raised to the top cap and there fastened by means of fusible metal such as lead shown at 29. If conditions in the line 23 are such as to cause the fusing and blowing of the fuse 27, the metal 29 holding plunger 27 to the top cap of the fuse, will release the plunger and permit the tension spring to take effect thus drawing the plunger downwardly. Normally, the lower cap of the fuse is connected through the plunger and fuse metal with the upper cap by means of a flexible wire 30. As the plunger is drawn down by the tension spring, a plug 31 held in place against the side of the body portion of the fuse by a compression spring 32, contacts the binding post 33 in the side of the body portion as shown by the fuse 25 in Fig. 2. At this time the current through the line 23 is short circuited into the fuse 25, fusing the metal which holds the plunger in the fuse 25 and causing that plunger to be drawn down by a similar tension spring in that fuse. In the same manner the contacting plug will short circuit the fuse 24 and cause a releasing of the plunger and the cutting of the entire current from the motor 34. In Fig. 2 the fuse 26 has been blown and the plunger has assumed its lowest position. In its downward travel it has short circuited the adjoining fuse 25 and has blown that fuse. The figure shows the second fuse plunger in the fuse 25 at a point in its downward travel where it would contact with the binding post 33 which causes the blowing of the adjoining fuse 24 and the fuse 24 is shown just before it has been blown. The operation of this system is identical to that shown in Fig. 1, the difference lying only in the details of construction of the individual fuses.

The functioning of the system is complete and satisfactory and its utility is readily appreciated when the blowing of three inexpensive fuses will prevent the burning out of the motor, an accident which requires the complete rewinding and substantial expense. 50

We claim as our invention:

1. Electric fuses for multiphase equipment, 55 consisting in fuses with line connections adapted to be interposed in the separate phase lines, spring means in each fuse and a fusible substance uniting the connections and said spring means and holding a spring tension 60 upon the latter, contacting means in each fuse and connections with the fuses in the other lines, whereby with the blowing of one fuse the connected lines are short circuited and the fuses blown. 65

2. Electric fuses for multiphase equipment, 70 consisting in fuses with line connections adapted to be interposed in the separate phase lines, spring means in each fuse and a fusible substance uniting the connections and said spring means and holding a spring tension upon the latter, contacting means in each fuse and connections with the fuses in the other lines, whereby the releasing of the spring means in one fuse with the blowing thereof, is 75 adapted to function through the contacting means and connections to successively short circuit the other phase lines.

3. Enclosed electric fuses for use in series 80 in multiphase systems, each fuse comprising a hollow shell closed by caps, projecting springs attached to the caps bent intermediate their length to contact and be fused with an electric connection inserted in the wall of the shell, an aperture on the wall of 85 the shell opposite the foregoing electric connection for inserting another electric connection with which latter one of the springs contacts when in normal position after the fuse has blown, to transmit current through said 90 electric connection, to the succeeding fuse or fuses in the series.
